TOY SUPPORT FOR PLAY BLOCKS

Frances L. Ilg, New Haven, Conn.

Application June 10, 1953, Serial No. 360,690

8 Claims. (Cl. 46—1)

This invention relates to an educational toy for small children and is more particularly concerned with a toy of the character indicated which will permit the child to exercise his creative talents and which will safely provide an outlet for the child's natural urge to knock down what he has created.

Experience with young children has shown that not only do they enjoy building, as with blocks, but also that they enjoy knocking down what they have built. When conventional building blocks are employed, the final knocking down of the blocks may injure the floor or the surrounding furniture, or other children in the vicinity. Moreover, the knocking down of a freely standing block structure may lead to excessive actions on the part of the child with undesirable results and damage. Young children also like to strike objects either with their hands or with some striking implement, such as a hammer. The release of this natural urge, if not controlled, may also have undesirable consequences.

It is an object of the present invention to provide a single, compact toy which will permit the safe and controlled release of the child's urge to build and to destroy what he has built, as well as his urge to strike.

It is another object of the invention to provide a toy of this nature which will also appeal to the child's creative talents and will provide an effective means for the development of these talents.

It is a further object of the invention to provide a new educational toy which will naturally and safely aid in the motor development of the young child.

It is another object of the invention to provide an educational toy which will assist in the development of the child's manual dexterity.

In accordance with the invention, there is provided a toy of the character indicated which comprises a case providing a sloping supporting surface for the reception of a plurality of blocks adapted to be arranged in predetermined relationship, a movable member for dislodging the blocks when arranged on the supporting surface, and means for actuating the movable member at the will of the child.

It is a feature of the toy of the invention that the movable member actuating means may be operated directly by the hand of the child or may be actuated by striking with an implement, as with a mallet or hammer.

It is another feature of the invention that the movable member effectively dislodges the blocks within a confined area and prevents their being flung with undesired force around the surrounding area.

It is a further feature of the invention that the blocks may be arranged on the supporting surface in a variety of relative relationships and thus provide means for the development of the child's creative talents as well as his perception.

Other objects and features of the invention will be readily apparent from the following description of illustrative embodiments of the invention and from the accompanying drawings, wherein,

2

Fig. 1 is a perspective view of an educational toy embodying features of the present invention;

Fig. 2 is a transverse sectional view, partly in elevation, of the toy shown in Fig. 1, the view being taken approximately through the center of the toy;

Fig. 3 is a perspective view similar to that of Fig. 1 but showing the blocks in place against the supporting surface;

Fig. 4 is a perspective view of another embodiment of the invention, showing a modified form of block dislodging means;

Fig. 5 is a transverse sectional view approximately through the center of the embodiment shown in Fig. 4;

Fig. 6 is a similar view of the embodiment of Fig. 4, showing the relationship of parts at the time the blocks are dislodged from the supporting surface by the child; and

Fig. 7 is a central transverse sectional view, similar to Figs. 2, 5 and 6, of another embodiment of the invention.

Referring to the drawings, and more particularly to Figs. 1 to 3, the reference numeral 10 designates generally the toy illustrated. Toy 10 is formed from two trapezoidal end walls 12 secured together by a top cross bar 14 and a partial back strip 16 connects the lower portions of the end walls 12. A bottom for the toy 10 and a support for the blocks 18 is provided by a slightly inclined bottom strip 20 which is received in lateral grooves 22 extending transversely of the end walls 12 adjacent their lower ends. As shown in the drawings, the bottom strip 20 extends from the back strip 16 and projects beyond the sides of the end walls for a short distance. An inclined lateral support for the blocks 18 is provided by a supporting wall 24 which, in the embodiment illustrated, is received in longitudinal grooves formed in the end walls 12, and the supporting wall 24 and the end walls are advantageously secured together, as by screws 25, to impart greater rigidity to the structure. It will be observed that in the embodiment of Figs. 1 to 3 the supporting wall 24 does not extend to the bottom strip 20 but terminates a small distance short of it to define an elongated slot 26, the purpose of which will be apparent as the description proceeds. Similarly, the supporting wall 24 is not flush with the side edges 27 of the side walls 12 but is spaced inwardly a short distance, as shown in Fig. 2.

Although the blocks 18 may be all of the same length, they are advantageously of at least two different lengths as shown in Fig. 3, the shorter blocks being about two-thirds to three-fourths the length of the longer blocks. In either case, the blocks are so dimensioned that the combined lengths of two or more blocks is equal to the distance between the side walls 12. Advantageously, as shown, a picture or indicia of some type is applied to the blocks so that each block forms a portion of a composite pictorial or other representation and the blocks thus represent portions of a simple jig-saw puzzle. When the blocks are laid up on the toy, as shown, they are supported from below by the bottom strip 20 and rest against the inclined support wall 24. The toy to the extent described thus provides a structure for block building and arrangement to develop the child's manual dexterity and perceptive abilities. As previously mentioned, the toy 10 also provides opportunity for the child to knock down the blocks which he has constructed in a safe and controlled manner. For this purpose, there is provided a pusher element 30 which is adapted to slide along bottom strip 20 and to project from the slot 26 to dislodge the blocks lying in front of the slot. The pusher element 30 is actuated by a vertically movable rod 32 which has an end which extends upwardly through an aperture in the cross bar 14. A spring strip 34, which may be formed

from spring steel or other convenient material, is connected to the lower end of rod 32 and to the pusher element 30 for normally retracting the pusher element and urging the rod 32 upwardly. Vertical movement of the rod 32 is guided by a block 35 which is secured to back strip 16 and is provided with an aperture 36 through which the rod passes. A knob 38 covers the upper end of rod 32 and serves to limit its downward movement, while providing a smooth striking surface.

When it is desired to dislodge the blocks 18 from their resting place against supporting wall 24, it is merely necessary to move the rod 32 downwardly. Such movement causes the pusher element 30 to move through the slot 26 and to strike the lowermost course of blocks, pushing these blocks forwardly away from the support wall. This will generally cause all of the blocks to fall off, but if the upper courses merely slide down and come to rest on the projection of the bottom strip 20, they are readily dislodged by repeated downward movement of the rod 32. As soon as pressure on the rod is released, it is returned to its initial upward position and the pusher element 30 is retracted by the action of spring strip 34. It will be apparent that the rod 32 may be moved directly by the hand of the child or that it may be moved by striking its upper end 38 with some other object. For this purpose there is conveniently provided a mallet 40 which is advantageously stored when not in use by passing its handle through an aperture in the top cross bar 14. When not in use the blocks may be stored in the space within the toy 10 defined by the end walls 12, back strip 16 and supporting wall 24. There is thus provided a compact, self-contained toy which is economical to construct and which provides an important need in the educational toy field. No matter how hard the rod 32 is struck to dislodge the blocks, none of the blocks will travel beyond a short distance of the supporting wall, with the result that danger of far-flying blocks is eliminated. The toy of the invention provides healthful and educational play means for the child, yet serves to confine the play activity within a limited area.

It will be obvious that various changes and modifications may be made in the embodiment illustrated in Figs. 1 to 3 without departing from the spirit and scope of the invention. The block dislodging means, for example, may take a form which varies somewhat from that in the embodiment above described. An embodiment of the invention having a block dislodging means of modified structure is shown, by way of example, in Figs. 4 to 6, wherein parts corresponding to those shown in Figs. 1 to 3 have been given like reference numerals to which 100 has been added. As illustrated in Figs. 4 to 6, the toy 110 has side walls 112, a top cross bar 114, a bottom 120, and a partial back strip 116 in the form and relative relationships of the corresponding parts shown in Figs. 1 to 3. The supporting wall, however, extends substantially to the bottom strip 120, and includes a pivoted central panel 124a which is hinged at its top, as by hinge 119, to top cross bar 114, being otherwise free from connection to the other portions of the toy, and stationary panels 124b. The panel 124a is thus free to pivot outwardly but is normally held in its inward position flush with the other portions of the supporting wall by a spring 121 which is secured to block 135 in which the rod 132 is guided. The panels 124b are suitably secured to side walls 112, bottom strip 120 and top cross bar 114. To dislodge the blocks, the central panel 124a is moved outwardly, as shown in Fig. 6. Referring more particularly to Figs. 5 and 6, the downward movement of the rod 132, when the knob 138 is struck by the child, is translated into outward movement of the central panel 124a by means of a cam arrangement comprising a cam member 141, which is secured to central panel 124a and which provides a tapered cam surface 142, and a cam follower 143 mounted upon the rod 132. A spring 144 between the cam follower 143 and the block 135 automatically returns the

rod 132 to its upward position upon release of the downward force upon it. Concurrently the cam member 141 moves upwardly and permits the central panel 124a to return to its normal inward position. The cam follower 143 normally serves as a stop for the inward movement of the central panel, although auxiliary stop means of any convenient type (not shown) may, if desired, be provided. While in the embodiment illustrated the central panel comprises about one-third of the supporting wall, it may be a greater or smaller portion of the wall surface. It should be sufficiently large, however, that it will strike a portion of all of the blocks upon its outward movement and will thus effectively dislodge them.

In another embodiment of the invention, illustrated in Fig. 7, features of the structure of Figs. 1 to 3 and features of the structure of Figs. 4 to 5 may be combined. Referring to Fig. 7, the toy 210 has a pivoted central panel 224a forming a portion of its block supporting wall as in Figs. 4 to 6, the panel 224a being hinged at 219 to top cross bar 214 and extending substantially to bottom 220. Outward movement of the central panel to dislodge the blocks is effected by means of rod 232 which rides in an aperture in block 235 and which is provided at its lower end with a pusher element 230 and a spring strip 234. The pusher element 230 has a width which corresponds to or is preferably less than the width of central panel 224a in order that it will not strike against the stationary panels on each side of the central panel. When the rod 232 is pushed downwardly, it causes the pusher element 230 to move outwardly and to strike against the lower end of central panel 224a, pivoting the panel outwardly as in Fig. 6. Upon release of pressure on pusher element 230 by rod 232, the rod moves upwardly and the pusher element is retracted by the action of spring strip 234. Spring 231 returns the panel 224a to its initial position. A stop 245 secured to one or both of the stationary side panels serves to prevent undesired inward movement of the central panel when the pusher element is retracted.

It will be apparent that various changes and modifications in addition to those already mentioned may be made in the embodiments described above and shown in the drawings without departing from the scope of the invention as defined in the appended claims. It will further be understood that, insofar as they are not mutually incompatible, the various features and details of construction of the several embodiments shown and described are interchangeable with one another. It is intended, therefore, that all matter contained in the foregoing description and in the drawings shall be interpreted as illustrative only and not as limitative of the invention.

I claim:

1. An educational toy comprising, in combination, a case defining a sloping supporting surface adapted to receive a plurality of blocks in substantially co-planar alignment, said supporting surface being at least in part provided by a panel pivoted in said case and carrying means defining a cam surface, means for supporting the lowermost of said plurality of blocks from below as they lie against said supporting surface, means for displacing at least the lowermost of said blocks away from said supporting surface, said last-named means comprising a cam follower engageable with said cam surface to displace said pivoted panel, and actuating means for effecting block-displacing movement of said means for displacing the blocks.

2. An educational toy comprising, in combination, a case defining a sloping supporting surface adapted to receive a plurality of blocks in substantially co-planar alignment, said supporting surface being at least in part provided by a panel pivoted in said case and carrying means defining a cam surface, means for supporting the lowermost of said plurality of blocks from below as they lie against said supporting surface, means for displacing at least the lowermost of said blocks away from said sup-

porting surface, said last-named means comprising a cam follower engageable with said cam surface to displace said pivoted panel, and actuating means for effecting block-displacing movement of said cam follower, said actuating means being a rod carrying said cam follower and vertically movable in said case, said rod extending upwardly from the case in position to be struck by a child to displace the blocks.

3. An educational toy comprising, in combination, a case defining a sloping supporting surface adapted to receive a plurality of blocks in substantially co-planar alignment, said supporting surface being at least in part provided by a panel pivoted in said case, means for supporting the lowermost of said plurality of blocks from below as they lie against said supporting surface, means for displacing at least the lowermost of said blocks away from said supporting surface, said last-named means comprising a pusher member movable into engagement with said panel, and actuating means for effecting block-displacing movement of said pusher member for displacing the blocks.

4. An educational toy comprising, in combination, a case, said case including a base adapted to lie in a horizontal plane and means defining a sloping supporting surface for receiving a plurality of blocks in substantially co-planar alignment, said supporting surface sloping inwardly from said base toward the central vertical axis of said case and having a horizontal dimension substantially as great as its vertical dimension, means extending from said case for supporting the lowermost of said plurality of blocks from below as they lie against said sloping supporting surface in co-planar alignment in a plane sloping from said last-named means toward said axis, means for displacing at least the lowermost of said blocks away from said supporting surface, said displacing means being normally urged by biasing means away from displacement movement toward said blocks, and manually-controlled actuating means acting against said biasing means for effecting block-displacing movement of said means for displacing the blocks.

5. An educational toy comprising, in combination, a case, said case including a base adapted to lie in a horizontal plane and means defining a sloping supporting surface for receiving a plurality of blocks in substantially co-planar alignment, said supporting surface sloping inwardly from said base toward the central vertical axis of said case and having a horizontal dimension substantially as great as its vertical dimension, means extending from said case for supporting the lowermost of said plurality of blocks from below as they lie against said sloping supporting surface in co-planar alignment in a plane sloping from said last-named means toward said axis, lateral guides for holding the blocks in lateral alignment on said sloping surface, means for displacing at least the lowermost of said blocks away from said sloping

supporting surface, said displacing means being normally urged by biasing means away from displacement movement toward said blocks, and manually-controlled actuating means actuatable against said biasing means for effecting block-displacing movement of said means for displacing the blocks, said actuating means comprising a rod vertically movable in said case and extending upwardly from the case in position to be struck by a child to displace the blocks from said supporting surface.

6. An educational toy comprising, in combination, a case, said case including a base adapted to lie in a horizontal plane and means defining a sloping supporting surface for receiving a plurality of blocks in substantially co-planar alignment, said supporting surface sloping inwardly from said base toward the central vertical axis of said case and having a horizontal dimension substantially as great as its vertical dimension, means extending from said case for supporting the lowermost of said plurality of blocks from below as they lie against said sloping supporting surface in co-planar alignment in a plane sloping from said last-named means toward said axis, lateral guides for holding the blocks in lateral alignment on said sloping surface, means for displacing at least the lowermost of said blocks away from said sloping supporting surface, said displacing means being normally urged by biasing means away from displacement movement toward said blocks, and manually-controlled actuating means actuatable against said biasing means for effecting block-displacing movement of said means for displacing the blocks, the lower end of said supporting surface being spaced from said means for supporting the lowermost blocks to define a slot therebetween, and said means for displacing the lowermost blocks comprising a pusher member movable through said slot against said biasing means into engagement with the blocks.

7. A toy as defined in claim 6, wherein said actuating means comprises a rod vertically movable in said case extending upwardly from the case in position to be struck by a child to displace the blocks and being flexibly connected at its lower end by said biasing means to said pusher member.

8. A toy as defined in claim 7, wherein said pusher member is an elongated strip and said biasing means is a metal spring strip normally urging said rod upwardly and said pusher member inwardly of said case.
